UNITED STATES PATENT OFFICE.

GEORGE J. CAPEWELL, OF CHESHIRE, CONNECTICUT.

TACK-EXTRACTOR.

SPECIFICATION forming part of Letters Patent No. 233,599, dated October 26, 1880.

Application filed July 27, 1880. (No model.)

To all whom it may concern:

Be it known that I, GEORGE J. CAPEWELL, a citizen of the United States, residing at Cheshire, in the county of New Haven and State of Connecticut, have invented certain new and useful Improvements in Tack-Drawers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to implements for drawing tacks out of floors and walls; and it consists in the construction and combination of parts hereinafter set forth and claimed.

In the accompanying drawings, Figure 1 represents a perspective view of my improved tack-drawer, and Fig. 2 represents the jaws thereof in detail.

A designates the stock or handle of the tool; B, a bifurcated jaw consisting of two parallel plates, b b, socketed into said stock, and C a single jaw pivoted between said plates. Each of said plates b is provided with a curved point, b', and the single jaw C is provided with a curved point, c, arranged opposite to said points b' b'. All of these three parts b b C are stamped or otherwise cut out of sheet metal of suitable thickness.

The jaw C is provided with a tail, C', which is curved to form a rocker-like fulcrum for compelling the point c of said jaw to close on the tack in the act of withdrawing the latter. The bifurcated jaw B passes under the head of the tack on both sides of its shank. Then a downward pressure on tail C' of jaw C causes

both jaws to bite the tack and pull it out of 40 the floor.

The relative positions of the single and the bifurcated jaws may be changed, and various modifications may be made in the forms of the several parts above named.

45 The tack-drawer thus constructed is cheaply manufactured, since nothing is required except to stamp out the parts C and b b by means of suitable dies from plates of metal, and then to fit them together on the stock, as stated.

50 The implement produced is very simple and very light, and its parts, if injured, are easily replaced. Thus the breaking or bending of one plate b will not make the other useless.

I am aware that implements have been constructed and patented for pulling spikes and 55 nails having a single jaw and a bifurcated jaw, as in the patent granted to W. Upton, dated April 16, 1878, No. 202,609; also, that a patent was granted G. Stone, January 31, 1865, No. 60 46,154, which shows a single jaw pivoted between the forks of a bifurcated fulcrum, the latter being provided with two rockers and a single jaw secured between them. I do not broadly claim either construction.

65 What I do claim, and desire to secure by Letters Patent, is—

The combination of sheet-metal plates b b, forming bifurcated jaw B, with single sheet-metal jaw C, provided with tail C' and pivoted between them, these three plates C b b constituting, with the stock A, the whole of the 70 tack-drawer.

In testimony whereof I affix my signature in presence of two witnesses.
